CLAIM

The ornamental design for a plastic audio cassette tape case, as shown and described.

DESCRIPTION

FIG. 1 is a perspective view of a plastic audio cassette tape case showing my new design;

FIG. 2 is a perspective view thereof shown in an open condition;

FIG. 3 is a reduced left side elevational view of FIG. 2, the right side being a mirror image;

FIG. 4 is a reduced top plan view of FIG. 2;

FIG. 5 is a rear elevational view of FIG. 1; and, FIG. 6 is a front elevational view of FIG. 1.

FIG 1

FIG 4

FIG 3

FIG 5
